William A. Utz
INVENTOR

UNITED STATES PATENT OFFICE

165,198

CAMPER'S TOOL

William A. Uttz, Fort Worth, Tex.

Application March 8, 1951, Serial No. 14,417

Term of patent 14 years

(Cl. D44—29)

To all whom it may concern:

Be it known that I, William A. Uttz, a citizen of the United States of America, residing at Fort Worth, in the county of Tarrant, and State of Texas, have invented a new, original, and ornamental Design for a Camper's Tool, of which the following is a specification, reference being had to the accompanying drawing, forming part thereof.

Figure 1 is a top plan view of a camper's tool, embodying my new design.

Figure 2 is a side elevation thereof.

Figure 3 is a bottom plan view thereof, and

Figure 4 is a front end view thereof.

I claim:

The ornamental design for a camper's tool, substantially as shown.

WILLIAM A. UTTZ.
